UNITED STATES PATENT OFFICE.

BERTHOLD P. BLAUERT, OF CHICAGO, ILLINOIS.

VALVE.

1,410,881.

Specification of Letters Patent. Patented Mar. 28, 1922.

Application filed June 19, 1920. Serial No. 390,239.

To all whom it may concern:

Be it known that I, BERTHOLD P. BLAUERT, a citizen of the United States, residing at Chicago, in the county of Cook and State of Illinois, have invented certain new and useful Improvements in Valves, of which the following is a specification.

This invention relates to valves which may be utilized for various purposes, but which are particularly adapted for use in connection with supplying water to concrete mixers. In supplying water to these machines, a measuring tank is ordinarily used which is filled from any suitable source of supply, and the water is then discharged from the tank into the mixer. This operation must be repeated very frequently, in some instances, about once a minute, so that quick operating valve mechanism is necessary. Furthermore, hot or cold water may be used, and the valve must be adapted to operate with either kind. Many of the ordinary valves which are now in common use, may operate successfully for cold water, but will not operate without considerable adjustment with hot water.

The objects of the present invention are to provide a quick operating multi-way valve which is adapted to be used with liquids or fluids under various temperatures; to provide a simple and efficient valve which will close one port and open another; to provide a valve for concrete mixers which will operate with either hot or cold water, and in general, to provide such an improved valve construction as will be described more fully hereinafter.

In the accompanying drawings illustrating this invention:

Figure 1 is a side view;

Figure 2 is a sectional plan view taken on the line 2-2 of Figure 1;

Figure 3 is a sectional view taken on the line 3-3 of Figure 2;

Figure 4 is a cross-section taken on the line 4-4 of Figure 3; and,

Figure 5 is a cross-section taken on the line 5-5 of Figure 3.

In accordance with my invention, I provide a valve body 6 which is preferably made of a single casting, and provided with the necessary passageways. The body has a chamber 7 at one end having an intake orifice 8, and an outlet orifice 9. The intake is threaded or otherwise constructed to receive an intake pipe 10 from any suitable source

of supply. The outlet orifice is also threaded to receive a pipe 11 which may lead to the measuring tank (not shown). The orifices 8 and 9, substantially constitute a through passageway which may be opened and closed by a suitable valve member, such as the slide valve 12, which is adapted to engage with seats 13. The valve slide 12 is preferably provided with guideways 14, to engage with guides 15 in the sides of the chamber 7. The valve slide 12 is connected to a valve rod 16 in any suitable manner, but preferably so as to allow sufficient play for the valve to seat properly. This is accomplished by having the rod 16 provided with a head 17 which engages with a recess 18 in the valve slide, as shown in Figures 3 and 5. The chamber 7 is closed at its outer end by a cap or bonnet 19, which has a suitable packing 20 for the valve rod 16.

The body 6 has a chamber 21 at the end opposite the chamber 7. The chamber 21 has an inlet port 22 which is connected by a passageway 23 with the port 9. It has an outlet port 24 which is arranged to receive an outlet pipe 25. The passageway provided by the ports 22 and 24 is opened and closed by a valve slide 26 which is a duplicate of the slide 12 and which is actuated by a rod 27. The chamber 21 is closed by a cap or bonnet 28 having a packing 29 for the rod 27.

Any suitable means may be provided for actuating the valves 12 and 26 simultaneously. In the arrangement shown, the rod 16 is connected to a cross-rod or arm 30. The ends of this arm are secured to rods 31, which extend longitudinally of the body, and are guided by bearings 32 on the sides of the body. The opposite ends of the rods 31 are connected by a pin 33, which passes through the rod 27. The body 6 has an arm or projection 34 to which is pivotally connected, an operating lever 35 having a slot 36 for receiving the pin 33. It will be seen that when the lever 35 is moved back and forth, it will cause the respective valves 12 and 26 to be alternately opened and closed.

When the device is used for a concrete mixer and the valves are in the position shown in Figure 3, the water will pass up through the pipe 10 and out through the pipe 11 into the measuring tank. When the tank has received the proper amount, the lever 35 is swung to the right, thereby closing the valve 12 and cutting off the supply.

This simultaneously opens the valve 26 and permits the water to pass in through the pipe 11 and passageway 23, and out through the pipe 25 to the mixer. It will be seen that 5 these valves may be operated very rapidly and on account of the valves being tapered to engage with tapered seats, they will tend to maintain tight closures, and will also operate successfully with either hot or cold water without any adjustment.

My improved valve may be made in various sizes, and different forms in order that it may be utilized for different sized machines and in different positions. Therefore, 15 I do not wish to be limited to the exact construction herein shown and described, except as specified in the following claims, in which I claim:

1. In a valve construction, the combination of a body having a passageway through 20 one portion thereof, a slide valve for controlling said passageway, a second passageway through another portion thereof, a slide valve for controlling said second passageway, valve stems connected by loose joints 25 to said slide valves and extending out through the body, means connecting said stems for operating them simultaneously, pipe connections leading from said passageways at one side of the body, a passageway 30 connecting said first named passageways at the other side of the body, and a pipe connection from said last named passageway.

2. A valve construction comprising a body 35 portion, having a chamber at one end thereof, an inlet orifice to and an outlet orifice from, such chamber, a tapered slide valve for controlling said inlet and outlet orifices, a valve rod connected with said valve

and extending out from said chamber, said body having a second chamber with an inlet and an outlet orifice, a tapered slide valve for controlling said orifices, a rod connected with said valve and extending out from the chamber, a passageway connecting the outlet orifice of the first chamber with the inlet orifice of the second chamber, a pipe connection from said passageway, a cross arm connected to the first-named valve rod, a pin through the second rod, longitudinal rods connecting said arm and pin and an operating lever connected to the pin for reciprocating said rods and valves.

3. The combination of a valve body having a chamber at one end thereof, an inlet orifice and an outlet orifice for said chamber, a tapered slide valve for opening and closing said orifices, a rod connected with said valve and extending out through the end of the chamber, said body having a second chamber in the opposite end thereof, an inlet orifice and an outlet orifice for said second chamber, the inlet orifice of the second chamber being connected with the outlet orifice of the first chamber, a tapered slide valve for opening and closing the orifices of the second chamber, a rod connected to said valve and extending out through the end of the chamber, a cross-piece connected to the first named valve rod, two rods connected to said cross-piece and extending longitudinally of the body, a pin connected with said last named rods and passing through the second valve rod, an arm projecting from said body and a lever pivoted to said arm and engaging with said pin for actuating the valves.

BERTHOLD P. BLAUERT.
